[57] CLAIM

The ornamental design for the locking button for a heatsink, as shown and described.

DESCRIPTION

FIG. 1 is a perspective view of a locking button for a heatsink showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a view showing the application of the locking button, wherein the broken line portion is for illustrative purposes only and forms no part of the claimed design.
